CLAIM

I claim the ornamental design for a Z locking house, as shown and described.

DESCRIPTION

FIG. 1 is an upper isometric view of the assembled Z locking house.

FIG. 2 is a lower isometric view of the assembled Z locking house.

FIG. 3 is a front view of the assembled Z locking house;

FIG. 4 is a rear view of the assembled Z locking house;

FIG. 5 is a right-side view of the assembled Z locking house;

FIG. 6 is a left-side view of the assembled Z locking house;

FIG. 7 is a top view of the assembled Z locking house; and,

FIG. 8 is a bottom view of the assembled Z locking house.

1 Claim, 8 Drawing Sheets
